UNITED STATES PATENT OFFICE.

HARRY J. RIMBACH, OF HAMMOND, INDIANA.

EXPLOSIVE-ENGINE.

1,215,993.

Specification of Letters Patent. Patented Feb. 13, 1917.

Application filed May 12, 1916. Serial No. 97,141.

To all whom it may concern:

Be it known that I, HARRY J. RIMBACH, a citizen of the United States, residing at Hammond, in the county of Lake and State 5 of Indiana, have invented certain new and useful Improvements in Explosive-Engines; and I do hereby declare the following to be a full, clear, and exact description of the invention, such as will enable others skilled in 10 the art to which it appertains to make and use the same.

This invention relates to improvements in engines of the internal combustion type, and more particularly to the construction of the 15 valves.

The invention has for its object to provide a novel type of rotary valve for explosive engines embodying a novel feature of construction, whereby the leakage of fuel 20 or the exhaust products of combustion past the valve is effectively prevented.

With this and other objects in view, the invention consists in the novel construction, combination and arrangement of parts as 25 will be hereinafter specifically described, claimed and illustrated in the accompanying drawing, in which:

Figure 1 represents a plan view of the engine, the top part of the valve casing being 30 removed and showing the valve partly in section,

Fig. 2 represents an end elevation of the engine,

Fig. 3 represents a vertical sectional view 35 therethrough,

Fig. 4 represents an enlarged detail sectional view showing the packing ring in position against the valve.

Fig. 5 represents a detail perspective view 40 of the head of one of the cylinders of the engine, illustrating one of the packing members in detail,

Fig. 6 represents a perspective view of the packing ring detached.

Referring to the drawings in detail, 45 wherein similar reference numerals designate corresponding parts throughout the several views, the numeral 5 indicates the cylinders of the engine, which are preferably of the waterjacketed type and receive the reciprocable pistons 6. The head of each cylinder is formed with exhaust and inlet ports 8 and 9, respectively, and the portions of the heads 7 overlying the ports 50 8 and 9 are cut away to present substan-

tially semicircular recesses 10 and 11 in which are partially received the hollow cylindrical valves 12 and 13. The upper portions of the valves 12 and 13 are inclosed in a housing 14, having apertures therein receiving bolts 15, whereby the housing is rigidly secured to the cylinder heads 7. 60

The inlet and exhaust valves 13 and 12 are formed with inlet and exhaust ports 17 and 16, which are adapted to be intermittently moved into registration with the inlet and exhaust ports 9 and 8 in the cylinder heads during rotation of the valves. One end of the valves is reduced, as indicated at 18, and are rigidly connected with gear 65 wheels 19, one of which is connected by a train of gears 20 with a pinion 21 on the crank shaft 22 of the engine, whereby the valves are mechanically operated during the 70 operation of the engine.

Each of the inlet and exhaust ports of the cylinder heads 7 is surrounded by a groove 23, which is preferably rectangular in shape and receives a correspondingly shaped packing ring 24, which is suitably curved to 75 snugly fit against the convex surface of the valve and is resiliently retained in engagement therewith by a plurality of springs 25 fitted in recesses in the bottom wall of the groove 23 and arranged underneath the corner of the ring. 80

What I claim is:

1. An explosive engine including a cylinder having a head and a substantially semicircular depression formed in said head, said head having a substantially rectangular port formed in the wall of said depression, and a groove surrounding said port, a valve rotatably mounted in said depression having a port therein adapted to be moved into registration with the first port, a substantially rectangular integral packing strip snugly received in said groove and engaging said valve, coil springs engaging the corners of said packing strip to retain said packing strip in engagement with the valve, and means to prevent the displacement of said springs. 90

2. An explosive engine including a cylinder having a head and a substantially semicircular depression formed in said head, said head having a substantially rectangular port formed in the wall of said depression, and a groove surrounding said port, a valve rotatably mounted in said depression having 100 105 110

a port therein adapted to be moved into registration with the first port, a substantially rectangular integral packing ring snugly received in said groove and engaged with said valve, and coil springs engaging the corners of said packing ring to retain said packing ring in engagement with the valve, the bottom wall of the groove having a series of recesses to snugly receive said springs,

whereby said springs are prevented from being displaced. 10

In testimony whereof I affix my signature in presence of two witnesses.

HARRY J. RIMBACH.
